UNITED STATES PATENT OFFICE.

ERNEST M. VIQUESNEY, OF SPENCER, INDIANA.

DESIGN FOR A STATUETTE, INCENSE BURNER, OR SIMILAR ARTICLE.

Application filed September 22, 1922. Serial No. 3,797. Term of patent 14 years.

To all whom it may concern:

Be it known that I, ERNEST M. VIQUESNEY, a citizen of the United States, residing at Spencer, in the county of Owen and State of Indiana, have invented a certain new, original, and ornamental Design for Statuette, Incense Burners or Similar Article, of which the following is a specification, reference being had to the accompanying drawing, forming part thereof.

Fig. 1 is a front perspective view of a statuette showing my new design;

Fig. 2 is a rear perspective view of the same.

I claim:

The ornamental design for statuette, incense burner, or similar article, as shown.

ERNEST M. VIQUESNEY.
